UNITED STATES PATENT OFFICE.

EMILE AUGUSTIN BARBET, OF PARIS, FRANCE.

CONDENSING ARRANGEMENT OF RECTIFYING APPARATUS.

Application filed February 2, 1920. Serial No. 355,548.

To all whom it may concern:

Be it known that I, EMILE AUGUSTIN BARBET, a citizen of the French Republic, residing at No. 5 Rue de L'Echelle, Paris, France, have invented certain new and useful Improvements in the Condensing Arrangements of Rectifying Apparatus, of which the following is a specification.

The present inventor is the author of a theory which was published by him a number of years ago. According to which, in rectifiers in alcohol and all other liquids, the condenser is considered not to be the seat of the refining operation, or if so, only to a comparatively negligible extent; purification being considered to take place practically entirely in the plates of the refining column, provided they are fed abundantly by the reflux of the condenser, which acts as a refining liquor.

Notwithstanding the clear proof of the above theory, rectifying apparatus have remained up to the present provided as before with a condenser and a cooler, whereas it would seem to be sufficient that they should comprise a single device serving to effect both condensation and cooling since no appreciable purification can be expected on the part of the condenser.

The obstacle to the adoption of this simplified arrangement has been that, in this case, the reflux of the single tubular apparatus is quite cold and on entering into the top of the rectifier, it would produce a rapid condensation of the ascending vapours, and consequently a relative vacuum which would prevent the reflux from descending successively into the lower plates.

But this effect becomes desirable applied to rectifying apparatus provided with cooling plates as described in the specification of Letters Patent No. 157,578 filed on 26th March, 1917, now Patent No. 1,328,259.

It is known that the partial condensation of a high degree alcoholic vapour upon a cool surface does not effect any analysis of this vapour and consequently no appreciable purification of this vapour is produced, but distillation, and especially distillation by bubbling, has, contrary to surface condensation, an analyzing power, that is to say, a very effective refining power.

Under these conditions the condensation of vapour which takes place within the liquid has the result of effecting distillation calorie for calorie.

In order to obtain the above results in actual practice, a certain number of plates of the rectifier are provided with worms for cooling the liquid thereon in order that the vapours shall bubble up through this liquid which is not quite as hot as the vapours.

The present inventor has previously caused water to flow through said worms, but the use of water is liable to cause incrustation of the tubes due to the deposit of lime and other impurities in the water, and this incrustation has to be removed from time to time.

One object of the present invention is to prevent such inconveniences and at the same time secure a reflux which is heated to a suitable temperature.

A further object of the invention is to avoid the deposition of incrusting matter from the cooling water in the device operating as condenser and cooler.

According to the present invention, a connection is provided between the device and the cooling worms adapted to cause the condensate to pass through the cooling worms, thereby cooling the liquid thereon and itself becoming heated and means are provided for returning the heated condensate to the top of the rectifier as reflux liquid.

In order to prevent the deposition of incrusting matter in the device performing the function of condenser and cooler according to the invention, means are provided whereby water is fed to this device in sufficient quantity to ensure that the water will pass out with a temperature lower than that at which the incrustations are formed, irrespectively of the temperature of the substance to be condensed.

In order that the invention may be clearly understood reference may be had to the accompanying drawings, in which

Figure 1 shows in elevation part of a rectifying apparatus arranged for carrying out the invention, and

Figure 2 shows a modified arrangement of the apparatus, the condenser, however, being omitted.

Fig. 3 is a vertical sectional view of a portion of a rectifying column with certain parts arranged slightly different from the form shown in Fig. 1.

Fig. 4 is a horizontal sectional view of the parts shown in Fig. 3.

As shown in Figure 1, the condenser B is of the tubular type, that is, one in which

the medium to be cooled circulates around tubes arranged in the condenser, the cooling medium flowing through said tubes. The cold reflux from B is caused to flow through 5 the worms of the plates so as to be heated thereby before returning to the upper plate of the rectifier A. The pipe M serves as the collector for the descending cold alcohol, and the pipe N serves as the collector for 10 the ascending heated alcohol.

A pipe d serves for drawing off the rectified alcohol for conveyance to the outlet test device D, the amount thus drawn off being regulated by means of the cock E 15 located at the entrance of the test device D. The whole of the remainder returns to the rectifier and constitutes the reflux thereof.

The condenser B must serve both as a condenser and as a cooler and must be regulated in such a manner that the lower part 20 of the apparatus shall always be cold. For this purpose, perforated diaphragms are arranged within the condenser casing, this construction reducing the amount of space 25 through which the medium to be condensed must circulate, and if necessary also an automatic regulation is provided by inserting a thermo-regulator T whose expansion has the result of operating the throttle P 30 located in the cold water inlet pipe, and thus controlling the admission of water into the tubes of the condenser B.

The use of a single apparatus for both condensing and cooling has another great 35 advantage, namely, that there is no longer any fear of sending an excess of water into the condenser B. In fact if there is sufficient water available, a copious admission of water may be employed so that the water 40 will pass out of the upper outlet pipe H at a temperature that is lower than that at which deposits of lime and other impurities begins to form in the tubes of the condenser.

In this manner daily cleanings of the 45 bores of the tubes of the condenser which is necessary at present owing to the fact that the water passes out of the condensers at a temperature of about 73/75° C. can be dispensed with.

This last advantage will be still more evident in those cases where rectification 50 of substances having a boiling point above 100° C. is effected, such as for instance of toluol, xylol, petroleum, etc. In the present-day rectifiers of these substances the water boils in the tubes of the condenser and thus causes still more rapid forming of deposits which it is absolutely necessary to remove. With the improved arrangement deposits 55 will no longer be formed since there is no objection to employing a copious admission of water.

However, in the case of the substances above mentioned the utility of cooling plates would 60 sometimes disappear owing to the fact that

the stages of the temperatures of rectification are more sharply defined than in the case of alcohol. A cold reflux may consequently be heated in a single tubular condenser J located at the upper part of the rectifier A. This tubular apparatus comprises a compartment fitted with tubes warmed by the passage of the vapours rising through A, the cold reflux being brought into contact with these tubes is slightly 70 warmed thereby. The arrangement will act as a pre-cooler without producing the above stated effects of vacuum. This improved arrangement is illustrated in Fig. 2 in which however the condenser B is not 75 shown.

Figs. 3 and 4 show one of the plates A² of the rectifying column with one of the cooling coils J. In these figures the pipes 80 M and N are both arranged on the same side of the rectifying column instead of on opposite sides, as in Fig. 1.

The improved method cannot be applied with the present-day duality of the condenser and the cooler because the excess of 90 water would prevent the cooler from receiving the slightest amount of steam and consequently the necessary issue of alcohol would be done away with.

In the foregoing description the application 95 of the invention to rectifiers of known design only of the discontinuous or continuous type has been dealt with.

In applying the invention to a continuous rectifier with pasteurization, the non-pasteurized alcohol will pass out through the pipe d and the test device D. But, as is usual in this process, the liquid alcohol known as "pasteurized alcohol" must be taken from one of the upper plates of the 100 rectifier, and a refrigerating device must be provided for this alcohol as well as a special test device for regulating its exit. This accessory apparatus which is well known is 105 not shown in the drawings.

Pasteurization consists in effecting the 110 final rectification of a liquid, not by means of a condenser, but on certain of the plates of the rectification column, and is obtained by returning to those plates a reflux of the 115 condensed vapours of the liquid, which condensate may contain some impurities. The vapours of the liquid being rectified and the vapours of other volatile fractions rising through the reflux driving off the impurities 120 therefrom and enabling the pure liquid to be drawn off from a point a few plates below the point of introduction of the reflux.

What I claim is:—

1. In combination with a rectifying column, a tubular condensing and cooling apparatus, means for withdrawing a portion of the cooled condensate from said apparatus elements in contact with the liquid 125

within the column, means for leading the remainder of the cooled condensate from said apparatus to said elements, and means for feeding said condensate after passage through said elements to the head of the rectifying column.

2. In combination with a rectifying column having plates, a tubular condensing and cooling apparatus, means for withdrawing a portion of the cooled condensate from said apparatus, coils arranged on the plates of the rectifying column, means for leading the remainder of the cooled condensate from said apparatus to said coils, and means for feeding said condensate after passage through said coils to the head of the rectifying column.

3. In combination with a rectifying column having plates, a single tubular condensing and cooling apparatus, means for circulating therethrough water at a temperature below that at which incrustations are formed, means for withdrawing a portion of

the cooled condensate from said apparatus, coils arranged on the plates of the rectifying column, means for leading the remainder of the cooled condensate from said apparatus to said coils, and means for feeding said condensate after passage through said coils to the head of the rectifying column.

4. In combination with a rectifying column having plates, a single tubular condensing and cooling apparatus, means for withdrawing a portion of the cooled condensate from said apparatus, a vertical header, a pipe leading the remainder of the cooled condensate to said vertical header, coils immersed in the liquid on the plates of the rectifier and connected at one end to said header, a second header connected to said coils and a pipe connecting said header to the head of the rectifying column.

In testimony whereof I have signed my name to this specification.

EMILE AUGUSTIN BARBET.
